Samuel L. Weiner, West Pittsburg, Pa.

Application October 19, 1956, Serial No. 43,425

Term of patent 14 years

(Cl. D87—6)

Fig. 1.

Fig. 2.

Fig. 1 shows a perspective view of the compartmented lid of a travelling case, including a flexible retainer for shoes, in exposed position; and

Fig. 2 is a perspective view of the compartmented lid in covered position.

The essential features of the design reside in the portions shown in solid lines on the drawings.

This application is a continuation-in-part of my application Serial No. D. 36,242, filed May 26, 1955, now abandoned.

I claim:

The ornamental design for a travelling case, as shown and described.
